OPERATION CONTROL INTERLOCKING
MECHANISM FOR POWER-OPERATED
TYPEWRITERS OR LIKE MACHINES

William H. Kupper, West Hartford, Conn., assignor to Royal Typewriter Company, Inc., New York, N. Y., a corporation of New York

Application July 9, 1952, Serial No. 297,828

4 Claims. (Cl. 197—17)

1

This invention relates to operation control interlocking mechanism for power operated typewriters or like machines, and more particularly to mechanism for interlockingly preventing effective depression of the typing or other keys of such machines when a switch controlling the power operated driving mechanism is shut off.

In one well-known class of power operated typewriters a driver such as a rotatable snatch roll is arranged to be operated continuously when the machine is in use. Instrumentalities adapted to be operated, such as the type bars, carriage returning mechanism, tabulating mechanism, case shifting mechanism, and back spacing mechanism, are connected to interponents which are adapted, upon depression of selected keys, to be moved into transient engagement with the snatch roll, whereupon the interponent and the instrumentality connected thereto are operated by the snatch roll. The operated interponent becomes disengaged from the snatch roll at the end of the operation, and returns to its normal position out of engagement with the snatch roll. If, when the electric motor for driving the snatch roll or other driver is not operating, a number of keys are held depressed, the associated interponents will be engaged with the stationary snatch roll so that if the power is then turned on and the motor started, a number of interponents and their associated instrumentalities will be actuated simultaneously, causing danger of jamming of the parts and damaging of the machine.

An object of the present invention is to provide improved mechanism for so correlating or interlocking a switch controlling the operation of the driving motor and a blocking element adapted to prevent depression of the keys that when the switch is in "off" position the blocking element is in blocking position, and so that when the switch is moved to "on" position the blocking element will be displaced so as not to be engageable by the keys.

Another object of the invention is to provide interlocking mechanism in connection with a snap action switch, which itself may be of conventional form, the parts being so related that the movable element of the switch, in passing from its "on" position through an intermediate position to its "off" position with a quick decisive action, insures movement of the key blocking element completely to its blocking position.

A further object of the invention is to provide mechanism of the kind referred to in co-operative association with mechanism respon-

2

sive to arrival of the carriage at its line end position for moving the key blocking element to blocking position irrespective of the position of the switch.

5 Other objects will become apparent from a reading of the following description, the appended claims, and the accompanying drawings in which:

Figure 1 is a fragmentary perspective view of 10 mechanism embodying the invention;

Figure 2 is a schematic view depicting electrically driven mechanism for operating the various typewriter instrumentalities;

Figure 3 is a fragmentary view, partly in top 15 plan and partly in horizontal section, on the line 3—3 of Figure 4, showing parts of a mechanism for positioning the blocking element in blocking position when the carriage reaches its line end position, and also showing parts of a margin releasing mechanism;

Figure 4 is a vertical section on the line 4—4 20 of Figure 3 with some parts shown in front elevation; and

Figure 5 is a view mainly in side elevation looking in the direction of arrow 5 in Figure 4 and showing a frame cross bar in vertical section.

A preferred form of mechanism constructed 25 in accordance with the invention is shown as being embodied in a typewriter only some of the conventional or usual parts of which are illustrated. Among the conventional machine parts shown are a stationary main frame, a part of which is shown at A, and a carriage mounted for letter spacing and return movement on the frame and including a right end plate 1 and a margin stop bar 2. Two operation initiating members, e. g. depressible key levers 3, are shown in Figure 1, but it will be understood that the machine includes the usual complement of key levers or like operation initiating members for operating or controlling the operation of the type bars and other usual mechanisms or instrumentalities.

The typewriter instrumentalities are adapted 30 to be operated by suitable power driven mechanism, for example electrically powered operating means of the kind disclosed in the patent to Kupper, No. 2,567,945, issued September 18, 1951. As illustrated schematically in Figure 2, a snatch roll 4 is adapted to be engaged selectively by actuator pawls, one of which is shown at 5. The snatch roll is driven by an electric motor 6 which transmits drive through a variable speed transmission 7, which may be of the kind disclosed in the patent to Hart, No. 2,573,197,

granted October 30, 1951. Conductors 8 and 9 lead from the motor 6 to a plug fitting 10 adapted to be connected to a power supply. A snap switch 11 is interposed in the conductor 9 and includes an arm part 12 formed with a ball shaped end. The switch may be of conventional construction and inherently has the operating characteristic of its arm 12 moving quickly and decisively from its "on" position through an intermediate position to its "off" position, and reversely.

Line locking mechanism for preventing operation of the keys 3 when the carriage has reached its line end position includes a center stop 13 pivotally mounted at 14 on a bracket 15 secured to the frame A. A line lock lever 16 is pivoted at 17 on the center stop 13 and has its upper end formed as a blade 18 normally spaced slightly from the top of the center stop 13 as shown in dotted lines in Figure 4. The blade 18 is disposed in the path of an adjustable abutment screw 19 on a right margin stop 20 adjustably positioned on the bar 2. The arrangement is such that when the carriage reaches the end of its letter spacing travel, as determined by the setting of the margin stop 20, the screw 19 will engage the lever blade 18 and rock the lever 16 counterclockwise, as viewed in Figure 1, until the blade 18 abuts against and is stopped by the upper end of the center stop 13.

The lower part 21 of the line lock lever 16 is formed with a rearwardly extending offset 22 connected to one end of a link 23, the other end of which is connected to the upper arm 24 of a lever, generally designated 25, pivoted at 26 and 27 on a frame mounted bracket 28. The lower arm 29 of the lever 25 is connected to the rear end of a link 30 having its front end connected to an ear 31 on a control element or blade 32 provided with pivots 33 and 34 adapted to be mounted in bearings (not shown) on the frame A. The control element 32 is urged to rock counterclockwise by a spring 35 interposed between the ear 31 and an anchor stud 36 adapted to be supported on the frame A. Thus, the spring 35 biases the blocking or key controlling element 32 forwardly from the position shown in Figure 1, so that normally, i. e., when the machine is in use, the top edge 37 of the blade 32 will be disposed clear of, that is, in front of, downwardly extending projections 38 on the key levers 3. A spring 39 interposed between an ear 40 on the bracket 28 and an ear 41 on the lever 25 urges the latter to rock in a direction to bias the link 30 forwardly and thus, additionally, to bias the line lock blade 32 to its normal position in which it does not prevent depression of the key levers 3. Movement of the blade 32 forwardly under the urge of the springs 35 and 39 is limited by engagement of a stop ear 25^a on the lever 25 with the bracket 28.

In operation, with the motor 6 and snatch roll 4 running continuously, the blade 32 will be in its forward or normal position so that the key levers 3 may be depressed. The top part 18 of the line locking lever 16 will be displaced to the right of the center stop 13 as indicated in dotted lines in Figure 4. When the carriage approaches the end of its letter spacing movement, the margin stop screw 19 will engage the top part 18 of the lever 16 so as to rock the latter in the manner previously described, thereby moving the link 23 toward the right, rocking the lever 25 so as to pull the link 30 rearwardly, and thereby rocking the line locking blade or control element 32 clockwise against the bias of the springs 35 and 39 to position the upper

edge 37 of the blade 32 under the key lever projections 38. In this manner, depression of the key levers 3 will be blocked or prevented when the carriage is in its line end position. When the carriage is moved to the right so as to relieve the pressure of the margin stop screw 19 on the part 18 of the lever 16, the springs 35 and 39 will restore the line lock blade 32 to its normal position determined by the stop ear 25^a.

Margin releasing mechanism is provided for enabling the line locking mechanism to be disabled at the will of the operator when the carriage is in its line end position and it is desired to type one or a few additional characters. In the form shown, the center stop 13 is provided at its lower end with a projection 42 which extends in front of the forward end of a pin 43 mounted for fore-and-aft sliding movement by a bearing 44 carried on the frame A. The rear end of the pin 43 has a head formed with a slot which receives the rounded end of an arm 45 of a lever, generally designated 46, pivotally mounted on frame A at 47. The other arm 48 of the lever 46 is provided with a pin 49 which is received in a slot 50 in an arm 51 of a lever, generally designated 52, pivoted at 26 on the bracket 28. The other arm 53 of the lever 52 is connected to the rear end of a link 54 the front end of which is connected to an upstanding arm 55 formed on a margin release key lever 56 pivoted on a screw 57 adapted to be mounted on the frame A. Movement of the key 56 is limited by a screw 58 extending through a slot 59 in the lever 56 and adapted to be mounted on the frame A. A spring 60 interposed between the arm 55 and a part 61 on the frame A normally maintains the margin release key lever 56 in the normal position shown in Figure 1.

If the carriage is in its line end position with the line locking blade 32 accordingly in its blocking or actuated position, and it is desired to type one or a few more characters, the margin release key 56 is depressed. This will pull forwardly on the link 54 so as to rock the lever 52 clockwise, and rock the lever 46 counterclockwise, thereby pushing the pin 43 forwardly, and rocking the center stop 13 so as to displace the center stop and the part 18 of the lever 16 from the path of the margin stop screw 19. This will both enable the carriage to move further to the left and enable the springs 35 and 39 to move the line locking blade 32 to its normal position, thus permitting the key levers 3 to be depressed.

In accordance with the invention, mechanism is provided for moving the line blocking blade 32 to blocking position when the switch 11 is set in "off" position, thereby preventing depression of the keys 3 when the machine is not conditioned for operation. In the form shown, a manually manipulatable device, e. g. a lever member 62, is pivoted on a screw 63 supported on the frame A. The front end of the lever 62 is provided with a finger piece or key 64, and an arm 65 at the rear of the lever 62 is pivoted at 66 to the upper end of a link 67, the lower end of which is pivoted at 68 to the front arm 69 of a switch operating lever 70, pivoted on a screw 71 carried by the main frame A. The rear arm 72 of the lever 70 is formed with spaced fingers 73 and 74 which straddle the ball end switch arm 12, the arrangement being such that when the lever 70 is rocked clockwise, as viewed in Figure 1, the finger 73 will press against the switch arm 12 to move the latter from its "off" position to its "on" position, whereas when the switch

arm is in its "on" position and the lever 70 is rocked counterclockwise, the finger 74 will move the switch arm 12 reversely to its "off" position. The inherent snap action of the switch arm 12 insures movement of the lever 12 completely from its "on" position, and vice versa.

When the parts are in the positions shown in Figure 1, the machine may be conditioned for operation by pushing downwardly on the finger piece 64, thereby rocking the lever 62 counterclockwise, lifting the link 67 and rocking the switch operating lever 70 clockwise. To return the switch to its "off" position, the finger piece 64 may be lifted, thus depressing the link 67 and rocking the lever 70 counterclockwise.

As previously explained, setting of the switch 11 in "off" position automatically positions the line locking blade 32 in its actuated or blocking position so as to prevent depression of the key levers 3-3 when the driving mechanism is not operating. As shown in Figure 1, an interponent lever 75 is pivoted on a screw 76 carried by the main frame A and has its rear arm 77 bifurcated at 78 to receive the pivot pin 68 which joins the lower end of the link 67 to the arm 69 of the lever 70. The front arm 79 of the interponent lever 75 is formed with an upstanding ear part 80 which underlies a tab part 81 riveted or otherwise secured to the line locking blade 32 in a position offset from the pivot axis 33-34. The upper operating face on the ear part 80 of the interponent lever 75 and the lower operating face on the tab 81 provide a one-way drive connection enabling clockwise rocking of the interponent lever 75 to move the blade 32 to its actuated or blocking position, but which nevertheless permits the blade 32 to be moved to its actuated position by operation of the link 39 and its associated elements independently of rocking of the interponent 75.

In operation, and assuming that the carriage is not in its line end position and assuming further that the finger piece 64 is in its "off" position, the related parts will be in the positions shown in Figure 1 with the switch arm 12 in its "off" position and the blade 32 held in its actuated position by pressure of the ear part 80 on the tab part 81. When the finger piece 64 is depressed, the link 67 is raised to rock the switch operating lever 70 clockwise so as to move the switch arm 12 to its "on" position. Raising of the link 67 also will rock the interponent lever 75 counterclockwise so as to lower the ear 80 and relieve its pressure on the blade tab 81, thereby permitting the springs 35 and 39 to rock the blade 32 counterclockwise and thus position the blade top edge 37 in front of and out of the paths of the key lever projections 38. Consequently the power driving mechanism will be set in operation and the key levers 3 will be conditioned for being operated in the usual manner. Movement of the blade 32 to its normal position will act through the link 39, lever 25, and link 23 to position the line lock lever 16 in its normal operation position shown in dotted lines in Figure 4.

When the machine is not to be used, the finger piece 64 is raised so as to lower the link 67, thereby rocking the switch operating lever 70 counterclockwise and moving the switch arm 12 back to its "off" position. Concomitantly, the interponent lever 75 is rocked clockwise, thereby raising its ear 80, and causing the latter to press against the tab 81 so as to rock the blade 32 against the urge of the springs 35 and 39 and position the top edge 37 of the blade under the 75

key lever extensions 38, thereby blocking depression of the keys. The inherent snap action characteristic of the switch arm 12 in moving decisively and quickly to its "off" position assures movement of the line locking blade 32 completely to its actuated position, so that even though the operator may carelessly not move the finger piece 64 completely from its "on" position to its "off" position, the blade 32 nevertheless will be moved completely to its actuated position.

If the switch is in its "on" position and the blade 32 is in its normal position, in which it does not prevent depression of the key levers 3, the lost motion connection 80-81 between the interponent lever 75 and the line locking blade 32 will permit the latter to be moved to its actuated position by the line locking lever 16 and its associated parts when the carriage reaches the end of its letter spacing travel.

The mechanism disclosed embodies the invention in a preferred form, but it is intended that the disclosure be illustrative rather than definitive of the invention. The invention is defined in the appended claims.

I claim:

1. In a power operated typewriter or like machine, electrically powered operating means; a switch for controlling operation of said operating means and having an "on" position and an "off" position; an operation initiating member; a control element settable in a normal position in which it does not prevent movement of said operation initiating member and in an actuated position in which it prevents movement of said operation initiating member; spring means for urging said control element to its normal position; a manually manipulatable lever; a lever for operating said switch; a link connecting said levers for conjoint operation; an interponent lever connected to and being operable by said link; and a part operatively associated with and being movable by said interponent lever for moving said control element to its actuated position against the urge of said spring means when said manually manipulatable lever, said link, and said switch operating lever are moved to operate said switch to its "off" position.

2. In a power operated typewriter or like machine, electrically powered operating means; a snap action switch for controlling operation of said operating means and having an arm movable from an "on" position past an intermediate position to an "off" position with a quick decisive action; an operation initiating member; a control element settable in a normal position in which it does not prevent movement of said operation initiating member and in an actuated position in which it prevents movement of said operation initiating member; spring means for urging said control element to its normal position; manually manipulatable means including a pair of spaced fingers straddling said switch arm and being operable for moving said switch arm to its "on" and "off" positions selectively; and an interponent operatively connected to said control element and to said manually manipulatable means and being operable by the latter for moving said control element to its actuated position against the urge of said spring means when said switch arm is moved to its "off" position, said switch arm, in moving quickly and decisively to its "off" position, acting through said manually manipulatable means to effect certain movement of said control element completely to its actuated position.

3. In a power operated typewriter or like ma-

chine, a stationary frame part; a carriage part movable with respect to said frame part during letter spacing carriage travel; a line locking device mounted on one of said parts for movement in response to arrival of the carriage at a predetermined line end position; electrically powered operating means; a switch for controlling operation of said operating means and having an "on" position and an "off" position; an operation initiating member; a pivoted control element settable in a normal position in which it does not prevent movement of said operation initiating member and in an actuated position in which it prevents movement of said operation initiating member; spring means for urging said control element to its normal position; a manually manipulatable lever; a link connected to said lever; a switch operating lever connected to said link and to said switch; an interponent lever connected to said link and having an operating face; an operating face on said control element offset from the pivot axis thereof and cooperating with the operating face on said interponent lever to provide a one way drive connection for moving said control element to actuated position when said switch operating lever moves said switch to "off" position, but said one way drive connection permitting movement of said control element to its actuated position irrespective of movement of said switch operating lever; and means connecting said line locking device to said control element for moving the latter to its actuated position when said line locking device is moved in response to arrival of the carriage at said predetermined line end position.

4. In a power operated typewriter or like machine, a stationary frame part; a carriage part movable with respect to said frame part during letter spacing carriage travel; a line locking device mounted on one of said parts for movement in response to arrival of the carriage at a predetermined line end position; electrically powered operating means; a snap action switch for controlling operation of said operating means and

having a switch part movable from an "on" position past an intermediate position to an "off" position with a quick decisive action; an operation initiating member; a pivoted control element settable in a normal position in which it does not prevent movement of said operation initiating member and in an actuated position in which it prevents movement of said operation initiating member; spring means for urging said control element to its normal position; a manually manipulatable lever; a link connected to said lever; a switch operating lever connected to said link and to said movable switch part; an interponent lever connected to said switch operating lever and having an operating face; an operating face on said control element offset from the pivot axis thereof and cooperating with the operating face on said interponent lever to provide a one way drive connection for moving said control element to actuated position when said switch operating lever moves said switch part to "off" position, said switch part, in moving quickly and decisively to its "off" position, acting through said switch operating lever, said interponent lever, and said one way drive connection to insure certain movement of said control element completely to its actuated position, said one way drive connection permitting movement of said control element to its actuated position irrespective of movement of said switch operating lever; and means connecting said line locking device to said control element for moving the latter to its actuated position when said line locking device is moved in response to arrival of the carriage at said predetermined line end position.
